Primary Examiner — Mehri F Bajoul*(74) Attorney, Agent, or Firm* — Justin Lampel**CLAIM**

The ornamental design for a toy gun storage bag as shown and described.

DESCRIPTION

FIG. 1 is a perspective view of a toy gun storage bag showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1; and, FIG. 10 is a perspective view shown in another state.

The broken lines depict portions of the toy gun storage bag and form no part of the claimed design.

The dot dash line is included for the purpose of illustrating the bounds of the enlarged view and forms no part of the claimed design.
